UNITED STATES PATENT OFFICE.

GEORGE ALDEN, OF WILKINSBURG, PENNSYLVANIA.

ATTACHMENT FOR TRUNKS.

SPECIFICATION forming part of Letters Patent No. 732,493, dated June 30, 1903.

Application filed May 6, 1903. Serial No. 155,844. (No model.)

To all whom it may concern:

Be it known that I, GEORGE ALDEN, a citizen of the United States of America, residing at Wilkinsburg, in the county of Allegheny and State of Pennsylvania, have invented certain new and useful Improvements in Attachments for Trunks, of which the following is a specification, reference being had therein to the accompanying drawings.

10 This invention relates to certain new and useful improvements in attachments for trunks, tool-chests, or analogous devices, and relates specifically to an attachment adapted to hold the lid of the article when opened in a position whereby the same is prevented from falling back in a manner which would damage the hinges thereof; and a further object of the invention is to construct a device serving this purpose and also the function 20 of locking drawers or slides in the trunk or chest when the lid is closed.

Briefly described, the invention comprises a barrel or sleeve which is attached to the inner face of the rear wall of the trunk or chest 25 and has arranged therein a vertically-operative spring-pressed plunger, to the upper end of which is connected a link which is attached to the compressing-plate that is attached to the lid of the trunk or chest. The spring- 30 pressed plunger is adapted to lock the slides or drawers of the trunk or chest when the lid is in the closed position, and the above and other details entering into my invention will be hereinafter fully described, and specifically pointed out in the claims.

In describing the invention in detail reference is had to the accompanying drawings, forming a part of this specification, and wherein like numerals of reference indicate 40 like parts throughout the several views, in which—

Figure 1 is a transverse vertical sectional view showing my attachment as applied to a tool-chest and showing in dotted lines the 45 manner in which the lid is supported when open. Fig. 2 is a front elevation showing the drawers removed and the front wall of the chest partly broken away.

To put my invention into practice, I provide a barrel or sleeve 1, which is suitably fastened to the inner face of the rear wall 2 of the chest or trunk. A convenient man-

ner of fastening the same I have found to be to provide the barrel or sleeve 1 with apertured lugs 3, which may be countersunk into the rear wall 2 and secured by screws or other suitable means, as shown. The lid 4 is suitably hinged to the rear wall 2 of the trunk or chest, and attached to this lid near its lower edge is a compression-plate 5, having a concave or depressed central portion 6 for engagement with the upper end of the spring-pressed plunger 7. This spring-pressed plunger 7 is arranged in the barrel or sleeve 1 and has its lower portion 8 reduced in diameter, with the spring 9 arranged thereon between the annular shoulder 10 and the lower end of the barrel or sleeve 1. The portion 8 of the plunger is extended beyond the lower end of the barrel or sleeve 1 and may be employed for the purpose of locking a series of drawers 11 in a manner as is clearly shown in Fig. 1 of the drawings. The plunger 7 has a screw 12 mounted in its upper end, provided with a head 14, with which is engaged a bail 15, that is connected to eyes 16, carried by the compressing-plate 5. It will of course be evident that the head could be formed direct on the upper end of the plunger 7, though I preferably construct the same 80 in a manner shown and described in order that any slight adjustment may be made, so as to cause the head 14 to center with the concave or dished face 6 of the compressing-plate. If the lid 4 of the trunk or chest is 85 unlocked, the spring 9, acting against the plunger, causes the lid 4 to fly open, due to the pressure of the plunger against the compressing-plate, and as the lid assumes the position shown in dotted lines it is there held 90 by the bail engaging with the head on the upper end of the plunger. The elevating of the plunger withdraws the portion 8 from engagement with the drawers and allows the same to be withdrawn, if desired.

In the practice of the invention it will be noted that various changes may be made in the details of construction without departing from the general spirit of my invention.

Having fully described my invention, what I claim as new, and desire to secure by Letters Patent, is—

1. In combination with a chest, a barrel or sleeve secured to the inner face of the rear

wall thereof, a spring-pressed plunger in said barrel or sleeve, a head carried on the upper end of the plunger, a compressing-plate carried by the lid of said chest, and a bail connecting said plate with the head of the plunger, substantially as described.

2. In combination with a chest, or the like, a barrel or sleeve secured thereto, a spring-pressed plunger in said barrel or sleeve, a head adjustably connected to the upper end of said plunger, a compressing-plate carried by the lid of the chest, and a bail connecting the plate to the head of the plunger, substantially as described.

15 3. In a device of the character described,

the combination with a chest, of a barrel or sleeve secured therein, a spring-pressed plunger within the barrel or sleeve and having its lower end extending below the end of the barrel or sleeve, a compressing-plate carried by 20 the lid of the chest, and connections between the said plate and the spring-pressed plunger, substantially as described.

In testimony whereof I affix my signature in the presence of two witnesses.

GEORGE ALDEN.
